UNITED STATES PATENT OFFICE.

DANIEL J. CRONIN, OF NEW YORK, N. Y., ASSIGNOR TO JOHN R. CLANCY,
OF SYRACUSE, NEW YORK.

SCENERY-CLEAT.

No. 838,846.

Specification of Letters Patent.

Patented Dec. 18, 1906.

Application filed September 28, 1905. Serial No. 280,547.

To all whom it may concern:

Be it known that I, DANIEL J. CRONIN, a citizen of the United States, residing at New York city, in the county of New York and State of New York, have invented certain new and useful Improvements in Scenery-Cleats; and I do hereby declare the following to be a full, clear, and exact description of the invention, such as will enable others skilled in the art to which it appertains to make and use the same.

My invention relates to cleats used on the wings of stage scenery by which the various wings are maintained in alinement and secured together to make up a complete scene; and it consists of a short flat bar having a roller at one end and formed at the other to receive the lash-line by which the sections are secured in position.

20 The construction of my cleat and the manner in which it is used are shown in the drawings herewith.

Figure I is a rear elevation of two wings provided with my cleats and lashed together. 25 Figs. II and III are respectively plan and side elevation of my cleat.

In the figures, 1 indicates the bar of the cleat of any desirable length, but commonly four inches, more or less, as the usual stile 30 2 of the frame of the wing 3 is three inches wide. The outer end of the bar is arranged to lie about flush with the outer edge of the stile, and on this outer end is secured the disk 4, which overhangs the edge of the stile 35 to engage with the stile of the next wing and maintain the two wings in alinement. The other end 5 of the cleat extends inwardly beyond the stile and may desirably be bent slightly outwardly and notched on its edges 40 the better to receive the lash-line. The cleat is provided with screw-holes for the securing-screws 6, and 7 is a hole in the disk registering with the outer screw-hole, through which the screw or bolt may be set in place. 45 The cleats are commonly arranged, as shown in Fig. I, in pairs on the respective wings. The upper pair are arranged farther

apart than the lower pair. A third pair might be added for drawing a bad joint when the stiles of the frames are sprung. 50 As the disks are journaled on the backs of the cleat-bars, the thickness of the bar permits a little play in the adjustment of the wings, which is desirable. Heretofore these alining cleats have been merely short pieces 55 of strap-iron which projected from the edge of the frame and caught on the floors, cardoors, &c., when the scenery was moved, which interfered with the moving, broke off the cleats, and injured the scenery and other 60 articles with which the cleats engaged. Also separate pieces were provided for the lashings. When the cleats were broken off they were lost and new ones had to be put in place. In the confusion of traveling plays 65 such supplies are often mislaid and the wings are imperfectly alined and secured.

My cleat of peculiar construction combines in one these two old parts—namely, the old straight cleat and the lashing-piece—and 70 overcomes the disadvantages mentioned. By the simple device of the roller on the end of the cleat injury and breaking off of the cleat is entirely overcome, and the wings may be turned on edge and rolled from place 75 to place, as on casters, instead of being lifted and carried.

Having thus described my invention, what I claim as new, and desire to secure by Letters Patent, is—

1. A scenery-cleat having in combination a flat, iron bar and a roller journaled to one end of the bar, said roller being arranged to project beyond the bar end, and the other end of the bar being slightly outwardly bent 85 and notched on its edges to receive the lash-line.

2. The combination with wings for stage-scenery having marginal stiles, of a scenery-cleat composed of a bar provided with screw-holes, and of a disk journaled at the outer end of the bar by an axle arranged at a right angle to the bar end, said disk extending beyond the stile edge, and screws for securing

the bar to the stile, said disk being provided with a screw-hole to register with one of the bar screw-holes, substantially as shown.

3. The combination with a scenery-wing,
5 of a cleat for alining the wings composed of a flat metallic bar, screws to secure the bar to the rear face of the stile with the bar end not projecting beyond the stile edge, and a thin, metallic disk journaled on the rear face of

the bar near the outer end, the disk being 10 journaled inwardly of the stile edge but having a portion projecting therefrom.

In testimony whereof I affix my signature in presence of two witnesses.

DANIEL J. CRONIN.
